UNITED STATES PATENT OFFICE.

FRANK PRIVRACKY, OF DICKINSON, NORTH DAKOTA.

SEWING KIT.

Application filed December 30, 1925. Serial No. 78,350.

This invention relates to certain new and useful improvements in sewing kits in the form of a receptacle to contain a spool of thread and accessories, such as buttons, snap fasteners, pins and the like and to be suspended by a chain worn about the neck of a seamstress for conveniently carrying the kit and rendering the same accessible for use at all times.

10 A further object of the invention is to provide a sewing kit in the form of a tubular receptacle having a removable transverse partition wall carrying a stem that rotatably supports a spool of thread within one end of the receptacle, each end of the receptacle being provided with a hinged cover.

The invention further includes the provision of cleats carried exteriorly of the receptacle upon one of which cleats thread 20 unwound from the spool can be attached while another of said cleats has needle supporting edges associated therewith, with thread in the needle wound on the cleat to retain the needle in position.

25 With the above and other objects in view that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views.

30 Figure 1 is a front elevational view of a sewing kit constructed in accordance with the present invention, the necklace or chain carrying the same being partly broken away,

Figure 2 is a front elevational view of the 40 kit showing a thread unwound from a spool supported within the kit passing through an opening in the side wall of the receptacle and attached to a cleat.

Figure 3 is a longitudinal sectional view 45 taken on line III—III of Fig. 2 showing the removable partition wall carrying the stem that supports the spool of thread and the separate compartments in the kit receptacle.

Figure 4 is a detail sectional view taken 50 on line IV—IV of Fig. 1 showing the needle supporting plate and the cleat carrying the same.

Figure 5 is a detail sectional view taken on 55 line V—V of Fig. 1 showing a clasp for supporting a thimble, and

Figure 6 is a detail sectional view taken on line VI—VI of Fig. 4.

Referring more in detail to the accompanying drawing, wherein is illustrated a preferred embodiment of the invention, the 60 reference numeral 1 designates the kit in the form of a tubular receptacle having hinged closure caps 2 and 3 for the opposite ends thereof. The receptacle 1 is carried by an ornamental chain 4 that is adapted to be 65 worn around the neck of the person using the kit so that the sewing accessories are readily accessible at all times.

As shown in Fig. 3, an internally threaded ring 5 is secured in the receptacle 1 and an externally threaded disk plate 6 in the form of a partition wall is threaded into the ring to divide the receptacle into separate compartments 7 and 8. To facilitate the mounting of the partition wall 6 in the ring 5, 70 said wall carries an elongated stem 9 having a key receiving outer end 10 to facilitate positioning thereof, the partition wall 6 further being provided with an annular flange 11 that overlies the adjacent side of 75 the ring 5.

When the cover 2 is open, a thread spool 12 is placed on the stem 9 as shown in Fig. 3 and the thread 13 issuing from the spool passes through the opening 14 in the wall 80 of the casing 1 and the free extended end of the thread 13 is wound around the cleat 15 as clearly shown in Fig. 2.

The needle support is carried exteriorly 85 of the casing 1 and is in the form of a cleat 16 shown in detail in Fig. 4 as having parallel side arms 17 provided with tubular openings 18 for the needles 19, the thread 20 carried by the needle being wound about the cleat 16 for securing the needles in position in the cleat.

As shown in Figs. 1 and 5, a spring clasp 21 carried exteriorly of the receptacle is adapted to support a thimble 22.

Various articles, such as buckles, buttons and clasps, pins, snap fasteners and the like may be carried in the compartment 8 while the thread spool 12 is supported upon the stem or spindle 9 in the compartment 7. The thread 13 from the spool passes through the opening 14 in the side wall of the case and may be used in the desired lengths, and when the kit is not being used, the end of the spool thread is anchored to the cleat 15. The needles 19 are retained in the tubular

openings 18 formed in the opposite sides 17 attached, and a necklace carrying the rest of the cleats 16 by the thread 20 carried by the needle attached to the cleat 16 as shown in Fig. 1. The kit is rendered extremely serviceable by the provision of the necklace or chain 4 to be worn around the neck of a person to render the same convenient in use.

While there is herein shown and described the preferred embodiment of the present invention, it is nevertheless, to be understood that minor changes may be made therein without departing from the spirit and scope of the invention as claimed.

15. What is claimed is:—

1. In a sewing kit, a receptacle, a partition wall in the receptacle dividing the same into two separate compartments, a hinged end cover for each compartment, a stem carried by the partition wall for supporting a thread spool in one compartment, said receptacle having an opening in the side wall thereof through which the thread from the spool is passed, a cleat positioned exteriorly of the receptacle to which the thread is

2. In a sewing kit, a receptacle, an internally threaded ring set into the receptacle, an externally threaded disk-shaped partition wall threaded into the ring to divide the receptacle into separate compartments, a peripheral flange carried by the partition wall overlying one side of the ring and a thread spool supporting stem extending axially from one side of the partition wall.

3. In a sewing kit, a receptacle, an internally threaded ring set into the receptacle, an externally threaded disk-shaped partition wall threaded into the ring to divide the receptacle into separate compartments, a peripheral flange carried by the partition wall overlying one side of the ring, a thread spool supporting stem extending axially from one side of the partition wall, a key receiving end on the stem, and a closure cap for each end of the receptacle.

FRANK PRIVRACKY.
